(57) **CLAIM**

The ornamental design for a drink mixer, as shown and described.

DESCRIPTION

FIG. 1 is a top and right side perspective view of drink mixer showing my new design;

FIG. 2 is a front-elevational view thereof;

FIG. 3 is a rear-elevational view thereof;

FIG. 4 is a right side-elevational view thereof;

FIG. 5 is a left-side-elevational view thereof;

FIG. 6 is a top-plan view thereof; and,

FIG. 7 is a bottom-plan view thereof.

The surface shading, if any, illustrated in the drawings is provided merely to highlight the contour of the design; it is not intended to be illustrative of texture or gloss.
